UNITED STATES PATENT OFFICE.

MAX PAUL ERNST HOHN, OF DRESDEN, GERMANY, ASSIGNOR TO "UNIVERSELLE"
CIGARETTENMASCHINEN-FABRIK, J. C. MÜLLER & CO.

ATTACHMENT FOR ROD CIGARETTE MACHINES.

Application filed December 11, 1923, Serial No. 679,927, and in Germany February 6, 1922.

In cigarette machines of the type in which cigarette or cigarette sleeves are formed into continuous rods, sections, each of the length of a cigarette, are cut in well known manner by circular knives which reciprocate in the transversal and longitudinal directions of the rod. The longitudinal reciprocating movement must be so controlled that during the cutting operation the knife will move 5 forwardly synchronously with the rod and that in the short interval during which the rod is fed the length of a cigarette the knife will move back to its initial position very rapidly. The control of the longitudinal reciprocating movement of the knife carrier presents difficulties which hitherto have not been overcome by various attempted constructions. The difficulties augment with the increase of the speed of the cigarette rod 10 so that for the modern rapid action machine the hitherto suggested means for controlling the longitudinal reciprocating movements of the knife have proved to be inadequate.

This invention relates to a novel means, 15 whereby in a comparatively simple manner the motions of the knife are controlled with great precision even at the highest speed of the rod. It consists in that the motion of the means engaging the knife carrier is controlled through the medium of a member, which is so connected to a rotary crank body 20 as to be adjustable diametrically relative thereto, the adjustment of said member being effected automatically through a stationary cam or the like. When said body revolves the member is adjusted by the stationary cam, so that the length of the crank arm 25 is changed. It is obvious that by correspondingly shaping the cam groove the longitudinal reciprocating movement of the 30 knife carrier can be made so that the latter during the cutting action will move synchronously with the rod and return rapidly to its initial position at the moment the rod 35 has advanced the length of a cigarette.

My invention will be more fully understood by reference to the accompanying drawing in which similar reference characters denote corresponding parts and in which 40 Fig. 1 is a side elevation; Fig. 1^a is an end view of the cutter carrier; Fig. 2 a horizontal cross section of one form of construction 45 of my control device; Fig. 3 a vertical sec-

tion of a modified construction and Fig. 4 a front view thereof. 55

Referring to the first form of construction shown in Figs. 1 and 2, *a* denotes a fixed fulcrum on which is rotatively mounted an oscillatory angle lever *b*. To one arm of this lever is connected a rod *c* by means of its forked part rotatively engaging a pivot *d* carried by a shoe *e*. The rod *c* has connected to it in well known manner the cutter carrier *c*¹ on which are supported the guide sleeves *c*² through which the cigarette rod 60 *R* passes. The circular knife *M*¹ is supported by a lever *L* from the carrier *c*¹ in well known manner so that it can be moved also transversely of the rod to perform the cutting operation. This shoe *e* is slidably mounted in a longitudinal slot *g* of the lever *b* and is adjustable therein through the medium of a screw spindle *f*. By the adjustment of the shoe or block *e* the mesne speed of the movement of the knife carrier 65 transmitted to the latter through said rod *c* can be varied. 70

The other arm of the lever *b* is also provided with a longitudinal slot *h* in which is slidably borne a block or shoe *i*. The latter is carried by a crank pin *k* which projects from a member *l* slidably mounted in a diametrically extending groove *m* of a crank disc *n*. This disc *n* is carried by the shaft *o* driven through bevel gears from a suitable 80 source of power (not shown). The disc *n* is formed with a radial slot *k'* through which passes the crank pin *k*. On its opposite side, the slide *l* carries a pin *p* which projects through a slot *p'* of the crank disc 85 *n* and carries a roller *q*. This roller engages a cam groove *r* provided in a stationary disc *s*. 90

When the shaft *o* and with it the disk is rotated the cam groove *r* in which the pin *p* 95 by its roller *q* is guided will cause the shoe or block *l* to reciprocate in the diametrical groove *m* of the disk *n*. This reciprocating motion will be transmitted to the block *i* by the crank pin *k* projecting from the shoe *l*, 100 in consequence of which the oscillatory movement of the lever *b* will be controlled according to the shape of the cam groove *r* which may be designed so that the rod *c* and therefore the cutter carrier *c*¹ will advance synchronously and longitudinally 105

with the rod during the cutting operation and on the completion of the latter return rapidly into initial position at the moment the rod has advanced a distance equal to the length of a cigarette.

It is clear that the cam groove *r* can be shaped to suit different requirements and that in some cases merely an adjustment of the cam disc will be sufficient without changing the disc itself.

In the modification shown in Figs. 3 and 4, the shaft *o* driven through the medium of bevel gears, carries the disc *n*. The crank pin *k* is carried by the member *l*, which is slidably mounted in the groove *m* arranged diametrically in the disc *n*. The pin *p* projects from the opposite side of the member *l* and carries the roller *q* engaging the cam groove *r* of the stationary disc *s*. Thus far the construction is identical with that of the heretofore described first form of construction.

Rotatively mounted on the crank pin *k* is a sleeve *2* from which projects the knife carrier *l*. This sleeve carries a rod *3* whose longitudinal axis is parallel to the plane of the circular knife *M*. The end *4* of said rod slidably engages a sleeve *5* carried by a horizontal pin *6*, which is rotatively supported in the bearing *7* arranged vertically below the center of the crank disc *n*.

In well known manner, the carrier *8* of the tube *9* through which the cigarette rod is fed is mounted on the horizontal rail *10* to be slideable longitudinally thereon. Fixed to the knife carrier *l* is a pin *11* whose free end projects into a slot *12* provided in the tube carrier *8*. The length of this vertical slot *12* is so admeasured that the pin *11* moving with the knife carrier through the crank pin *k* and which in well known manner effects the feed of the tube carrier *8* is permitted to reciprocate vertically. According to this invention, the pin *11* is so arranged on the knife carrier, that its axis is even with the cutting line of the circular

knife. Thereby the tube during the cutting operation may be made to move synchronously with the knife and correspondingly also with that of the rod.

With this second modification, the angle lever and connecting rod are dispensed with and the knife carrier is directly applied to the crank pin *k*.

What I claim is:—

1. In a rod cigarette machine, the combination with the cutter carrying means, of a device for controlling the movement of said means, comprising a rotary member formed with a diametrical recess and a cam controlled crank pin slidably supported in said recess and adapted to transmit motion to said cutter reciprocating means.

2. In a rod cigarette machine, the combination with the cutter carrying means, of a device for controlling the movement of said means, comprising a rotary member formed with a diametrical recess, a cam controlled crank pin slidably supported in said recess and means engaging said crank pin and operatively connected to said first named means.

3. In a rod cigarette machine, the combination with the cutter carrying means, of a device for controlling the movement of said means, comprising a rotary diametrically recessed disc, a cam controlled member slidably mounted in the recess of said disc and a crank pin carried by said member and actuating said first named means.

4. In a rod cigarette machine, the combination with the cutter carrying means, of a device for controlling the movement of said means, comprising a rotary diametrically recessed disc, a member slidably mounted in the recess of said disc, a cam actuating said member, a crank pin carried by said member and a lever mechanism actuated by said crank and operatively connected to said first named means.

In testimony whereof I affix my signature.

MAX PAUL ERNST HOHN.
